(57) **CLAIM**

The ornamental design for a dessert fork with slotted pattern, as shown and described.

DESCRIPTION

FIG. 1 is a side view of the dessert fork with slotted pattern showing my new design, the opposite side view being a mirror image thereof.

FIG. 2 is a perspective view of the dessert fork with slot pattern.

FIG. 3 is top plan view of the dessert fork with parallel slot pattern.

FIG. 4 is a bottom view of the dessert fork with parallel slot pattern.

FIG. 5 is an enlarged front view of the dessert fork with slotted pattern; and,

FIG. 6 is an enlarged rear view of the dessert fork with slotted pattern.
